UNITED STATES PATENT OFFICE

HARRY SMALLMAN, OF PHILADELPHIA, PENNSYLVANIA, ASSIGNOR TO HILL INDEPENDENT MANUFACTURING COMPANY, OF PHILADELPHIA, PENNSYLVANIA, A CORPORATION OF PENNSYLVANIA

HAND STAMP

Application filed June 12, 1930. Serial No. 460,677.

My invention relates to improvements in hand stamps.

The object of my invention is to provide a hand stamp with means for regulating the tension of the bands which carry the printing characters.

Heretofore, such stamps have been commonly made and used for date stamps, but the fault with such stamps has been that with 10 use the bands carrying the printing characters have deteriorated and become stretched and loose, so that they would no longer be turned and adjusted by manipulation of the turning rolls.

15 By the use of my invention, the tension on the print bands may be either increased or decreased by turning the handle of the stamp either to the right or left. By increasing the tension on the bands they are held securely in 20 position for use.

In the accompanying drawing:

Fig. 1 is a perspective view of the assembled device;

Fig. 2 is a vertical cross section;

25 Fig. 3 is a transverse vertical cross section;

Fig. 4 is a disassembled perspective view of saddle and nut; and

Fig. 5 is a detached perspective view of print bar.

30 The main frame of the device is made of one piece of sheet metal which is bent into the proper shape. The sheet metal is bent so as to have a flat top portion 2 and two arms 4 perpendicular thereto. The outward ends of 35 the arms 4 are notched as at 6 to engage the print bar 8, over which the print bands 10, which carry the characters 12, ride and are held in proper position to be used.

The print bar 8 has shoulders 14 to engage 40 the inner sides of the arms 4 and lugs 16 to engage the outer sides thereof, thereby holding the bar 8 firmly in position.

The bands 10 pass over the bar 8 at the outer ends of the arms 4, the inner ends of 45 the bands passing over the knurled rollers 18, each of which is permanently secured to a knurled wheel 20.

The knurled rollers 18 are mounted on the shaft 22, which is guided at either end by the 50 groove 24, which groove is formed by the

stamped off-set 25 in the arms 4. The shaft 22 is held in position and pulled against the force of the print bands by the saddle 26, through the holes 27 of which the shaft 22 passes, the saddle straddling two of the rollers 18 on the center of the shaft. The nut 28 passes through the hole 30 in the saddle, which hole fits the flat sides of the nut to prevent the latter from turning, the shoulders 32 of the nut engaging on the inside of the 55 saddle.

The nut passes through the top portion 2 of the frame and is engaged by the bolt 34 which passes through the handle 36 rigidly secured thereto, which handle has a recess 38 at its inner end providing clearance space for the nut 28 when the same is pulled through the saddle 26 and the top plate 2 of the main frame by the turning of the handle 36 and the bolt 34. The inner end of 60 the handle bears and turns on the plate 2 of the main frame.

65 By turning the handle 36 in a clockwise direction, the nut 28 will be drawn through the top plate 2, thus pulling the saddle 26 and the shaft 22, which in turn will pull against the print bands 10 which are carried on the rollers 18 on the shaft 22. The other ends of the print bands 10 ride over the print bar 8 and are thus held tightly in position, 70 since the print bar 8 may not be moved toward the handle 36. In other words, the tension on the bands 10 is applied or released with substantial uniformity by simply turning the handle 36 to the right or 75 left.

75 It will be readily understood that my invention may be used for any kind of hand stamp, where it is desirable to change the printing characters from time to time and 80 is not limited to the particular form shown 85 which is a date stamp.

I claim:

1. A hand stamp comprising a printing band roll, a saddle supporting the roll and 90 having an opening in the top thereof, a nut having a portion extending through the opening and supporting the saddle, and a handle having screw-threaded connection with the nut for adjusting the position of the saddle. 100

2. A hand stamp comprising a printing band roll, a shaft therefor, a saddle supporting the shaft and having an irregular shaped opening in the top thereof, a nut having a flattened portion fitting and extending through the opening and supporting the saddle, and a handle provided with a rod having screw-threaded engagement with the nut for adjusting the position of the saddle.
3. In a hand stamp, a printing band roll, a saddle supporting said roll, and having an opening therein, a nut having a portion extending through the opening, lugs formed on the inner end of the nut for supporting the saddle, means for preventing relative turning between the saddle and nut, and a handle provided with a rod having screw-threaded engagement with the nut for adjusting the position of the saddle.
4. A hand stamp comprising a frame having an opening in the top thereof, printing band rolls, a shaft extending through said rolls, a saddle supporting said rolls and having an irregular shaped opening therein, a nut having a portion extending through the opening in the saddle and the top of the frame, lugs formed on one side of the nut for supporting the saddle, and a handle provided with a rod having screw-threaded engagement with the nut for adjusting the position of the saddle.
5. A device of the character described including a substantially U-shaped frame, a bar extending between the arms of said frame, said arms having guides throughout substantially their entire length, a shaft mounted between said arms and slideable on the said guides, a plurality of rollers carried by said shaft, and endless print bands extending over said rollers and bar.
6. A device of the character described including a one-piece metal frame, bent to substantially U-shape, a bar extending over the outer ends of the U-shaped frame, grooves formed in the inner sides of the arms of the frame, and extending to the outer ends thereof, rollers mounted within said frame and carried on a shaft, the outer ends of said shaft sliding within said grooves, print bands carried by said rollers and bar, and means for changing the position of said shaft relative to said bar.

In testimony whereof I affix my signature.
HARRY SMALLMAN.
